United States Patent Office

Des. 224,926
Patented Oct. 17, 1972

224,926

BREAKFRONT ARMOIRE OR THE LIKE

Joseph E. Adkinson, 3807 Leland St.,
Chevy Chase, Md. 20015

Filed Aug. 13, 1970, Ser. No. 24,472

Term of patent 14 years

Int. Cl. D6—04

U.S. Cl. D6—169

The figure is a perspective view of a breakfront armoire showing my design.

The side not shown is like the side shown, while the top and back are plain and unornamented.

I claim:

The ornamental design for a breakfront armoire or the like, substantially as shown and described.

References Cited

UNITED STATES PATENTS

D. 178,355 7/1956 Gaines ----- D33—7

OTHER REFERENCES

“French Provincial” by Kindel, rec'd July 26, 1963, buffet/hutch No. 31-25.

“Trieste” by American of Martinsville, dated June 1969, buffet/hutch No. 2451-401.

BRUCE W. DUNKINS, Primary Examiner